UNITED STATES PATENT OFFICE.

EDWARD N. JACOBI, OF MILWAUKEE, WISCONSIN, ASSIGNOR, BY MESNE ASSIGNMENTS, TO BRIGGS & STRATTON CORPORATION, OF MILWAUKEE, WISCONSIN, A CORPORATION OF DELAWARE.

DESIGN FOR AN AUTOMOBILE INSTRUMENT-PANEL RIM.

Application filed January 5, 1923. Serial No. 4,815. Term of patent 3½ years.

To all whom it may concern:

Be it known that I, EDWARD N. JACOBI, a citizen of the United States, residing in Milwaukee, in the county of Milwaukee and State of Wisconsin, have invented a new, original, and ornamental Design for Automobile Instrument-Panel Rim, of which the following is a specification, reference being had to the accompanying drawing, forming part thereof.

The figure is a front view of an automobile instrument panel rim, showing my new design.

I claim:

The ornamental design for an automobile instrument panel rim, as shown.

EDWARD N. JACOBI.
